Primary Examiner — George D. Kirschbaum*Assistant Examiner* — Darcey E Heflin(74) *Attorney, Agent, or Firm* — The Watson IP Group, PLC; Jovan N. Jovanovic; Vladan M. Vasiljevic(57) **CLAIM**

The ornamental design for a cap for a pouch, as shown and described.

DESCRIPTION

FIG. 1 of the drawings is a front perspective view of the cap for a pouch showing, in particular, the ornamental design thereof;

FIG. 2 of the drawings is a front elevational view thereof; FIG. 3 of the drawings is a back elevational view thereof; FIG. 4 of the drawings is a first side elevational view thereof; FIG. 5 of the drawings is a second side elevational view thereof;

FIG. 6 of the drawings is a top plan view thereof; and, FIG. 7 of the drawings is a bottom plan view of the thereof. The dashed lines show features that form no part of the claimed design.

1 Claim, 6 Drawing Sheets(56)
